UNITED STATES PATENT OFFICE.

WILLIAM E. LAUTENSCHLAGER, OF CINCINNATI, OHIO, ASSIGNOR TO LORENZ MUTHER, OF BOSTON, MASSACHUSETTS.

STITCHING FOR SECURING SHANK-EYE BUTTONS AND METHOD OF FORMING THE STITCHING.

1,242,565.

Specification of Letters Patent.

Patented Oct. 9, 1917.

Application filed December 29, 1913. Serial No. 809,284.

To all whom it may concern:

Be it known that I, WILLIAM F. LAUTENSCHLAGER, a citizen of the United States, residing at Cincinnati, in the county of Hamilton and State of Ohio, have invented certain new and useful Improvements in Stitching for Securing Shank-Eye Buttons and Methods of Forming the Stitching, of which the following is a specification.

10 My invention relates primarily to stitching for securing shank-eye buttons to shoes and to the method of attaching such buttons to the shoe, and I have shown and described my invention with relation to such 15 use from which its application to shank-eye buttons in other relations may be readily perceived.

It is one of the objects of my invention to secure shank-eye buttons in place in a novel 20 manner so that the eye of the button is affixed closely to the surface upon which the same is secured. It is a further object of my invention to provide a novel stitching and method of forming the same whereby 25 the stitching for each button independently secures the button in place; further to provide a novel stitching and method of forming the same whereby each button is maintained in place by a knotting in the stitching; further to provide a stitching and 30 method of forming the same for securing the shank-eye button in place by means of a single thread so manipulated as to pass a plurality of the stretches of a loop of the 35 thread through the shank-eye of the button and through the material at both sides of the shank-eye; and, further to secure the loop in place below the surface at which the button is located.

40 I have shown and described one form of my improved stitching and method of forming the same in a separate application executed by me of even date herewith, being Serial No. 809,283, filed December 29, 1913, 45 and have broadly claimed my improved stitching and method of forming the same in said application. The stitching and method of forming the same herein shown and described and claimed is an elaboration 50 upon the stitching and method of forming the same shown and described in my other aforesaid application and differs in some particulars therefrom.

The stitching may be formed manually or by machinery, as may be desired, although 55 in the ordinary course of manufacture the stitching will be more generally accomplished by suitable machinery or combinations of devices for acting on the thread. I have not herein shown any mechanism for 60 manipulating the thread in accomplishing the desired results, as any mechanism suitable for the purpose may be employed.

I have, in the drawings, illustrated various stages in the course of the formation of 65 the stitching, these stages being selective or arbitrary stages selected at points in the formation of the stitching which will most clearly show the manipulation of the thread, it being understood that, especially when 70 the stitching is formed by machinery, the operations or manipulations preferably take place in a continued and uninterrupted series of steps for forming the stitching.

The invention will be further readily 75 understood from the following description and claims, and from the drawings, in which latter:

Figure 1 is a perspective view showing a primary loop of the thread received through 80 the material, the latter being shown in vertical section taken on the line of the stitching, and partly broken away, it being assumed that a previous button has been attached to the material and the thread to 85 form the stitching led therefrom for forming the stitching to be described.

Fig. 2 is a similar view showing the button with its eye received about the loop.

Fig. 3 is a similar view showing the primary loop flexed in the line of feed preparatory to being received reversely through the material.

Fig. 4 is a similar view with the loop received reversely through the material. 95

Fig. 5 is a similar view showing a secondary loop received through the primary loop, with the slack drawn out of the primary loop.

Fig. 6 is a similar view showing the secondary loop flexed reversely for forming a knot between one of the stretches of the secondary loop and the primary loop. 100

Fig. 7 is a bottom view of the same.

Fig. 8 is a perspective view showing the 105 secondary loop flexed reversely in the path

of the stitching and spread for receiving a tertiary loop therethrough, the material being shown in vertical section in the line of the stitching, and partly broken away.

5 Fig. 9 is a bottom view of the same.

Fig. 10 is a perspective view, showing the tertiary loop passed through the secondary loop and through the material to that side thereof at which the button is being secured, 10 the material being shown in vertical section on the line of the stitching, and partly broken away.

Fig. 11 is a similar view, showing the secondary loop knotted and the tertiary loop 15 flexed parallel to the path of the stitching and spread for being received about the button.

Fig. 12 is a plan view of the same with the head of the button broken away.

20 Fig. 13 is a perspective view with the tertiary loop pulled tight and the tertiary knot formed, and showing the completed stitch, the material being shown in vertical section on the line of the stitching.

25 Fig. 14 is a bottom view of the same.

Fig. 15 is an enlarged perspective view of the completed stitching, showing the head of the button broken away and showing the material in dotted lines for better illustration

30 of the stitching; and,

Fig. 16 is a plan view of the stitching, the heads of the buttons being broken away, shown in connection with the coöperating shoe part having the button-hole therein.

35 While the stitching of my improved method may be accomplished either by manual manipulation or by the operation of mechanical means, it will be assumed for convenience of description, that the stitching is being formed by suitable mechanism in which the material, shown at 11, is fed in the direction of the arrow *a*. This material may be the quarter of a shoe. It will be further assumed that a preceding button 40 or buttons have been attached to the material, and that the stretch 12 of the thread, the latter indicated generally at 13, passes from the stitching of a preceding button to the position at which the stitching for the 45 button being secured in place is located. It will be further understood that stitching, which I illustrate in the drawings, is formed by a single thread, which may have its source at a bobbin or spool.

50 At the point where the stitching to be formed is located, the thread is passed through a hole 14, suitably formed in the material either concurrently with or independently of the passing of the thread 55 through the hole, depending on whether a thread-needle or a hook-needle is employed for the purpose. The thread is received through the hole for forming a primary loop 15, (see Fig. 1).

60 The shank-eye 16 of the button 17 is located

about the primary loop, (see Fig. 2). This may be accomplished concurrently with the passage of the primary loop through the hole 14 or after the primary loop has been received through the hole. The shank-eye 70 of the button is arranged crosswise of the stitching, its rounding 18 being arranged to be received under the primary loop and to extend crosswise of the stitching so as to be secured with its shank-eye in line with the 75 button-hole 19 in the coacting flap 20 of the article. This coacting flap may represent the button-fly of the shoe. The rounding is thereby placed close to the outer face 21 of the material.

80 The primary loop 15 is then deflected lengthwise of the path of the stitching, (see Fig. 3), which path is indicated by the dotted line 22 in Fig. 12, and is received reversely through the material through a hole 85 23, (see Fig. 4), distanced from the hole 14 a distance corresponding to the length of the stitching, which is ordinarily from three-sixteenths to a quarter of an inch, when stitching shoe-buttons. The primary loop 90 may be either pulled or pushed through the hole 23, depending on the instrument employed, if mechanical means or a tool is used for accomplishing the purpose.

95 By the means so far stated both stretches of the primary loop are received through the material in reverse directions at the respective sides of the shank-eye of the button and the rounding of the button-eye received under both said stretches. The primary loop is 100 for convenience described as comprising an initial stretch 24 and a supply stretch 25.

105 A secondary loop 26 extends from the primary loop. For forming this secondary loop I prefer to lead a portion of the supply stretch 27 of the thread through the primary loop from that side of said primary loop presented toward the hole 14 (see Fig. 5). The secondary loop is preferably formed in great part by drawing upon the primary 110 loop for stretching the same across the outer surface of the intermediate portion 28 of the material to which the button is secured, this intermediate portion being located between the holes 14 and 23, and placing the bight 115 of said primary loop proximate to the second hole of the stitching.

120 The secondary loop is flexed in reverse direction, as indicated at 31, (see Fig. 6), and pulling strain preferably exerted upon the same for stretching the stretches of the primary loop and forming a knot 32 between the primary loop and the secondary loop, this knot being preferably formed below the surface 21 of the material at the bight 33 of 125 the primary loop between the primary loop and the initial stretch 34 of the secondary loop. The rounding 18 of the shank-eye of the button is thereby firmly pressed against the surface 21 of the material. This reverse 130

stretching of the secondary loop preferably locates this knot under the intermediate portion 28 of the material.

The secondary loop is spread, as shown at 37, for receiving a tertiary loop 38 of the thread therethrough. (See Figs. 8 and 9.)

The tertiary loop is passed through the material to that side thereof at which the button is located, and preferably through the hole 14 alongside the stretches of the thread theretofore passed through said hole, (see Fig. 10), as indicated at 39.

The needle having been withdrawn from said hole, if a needle is employed in the operation, a pulling is exerted upon the tertiary loop, whereby the bight of the secondary loop is drawn toward the bight of the primary loop and the secondary loop drawn taut, forming a knot 40 between the supply stretch 41 of the secondary loop and the thread of the primary loop, and a further knot 42 formed between the initial stretch 43 of the tertiary loop and the thread of the secondary loop. The knots 32, 40 and 42 are located preferably adjoiningly, and preferably form a compound knot between the primary loop and the loop 38. The loops 15 and 38 are shown arranged in concatenated relation. (See Fig. 11.)

The bight portion of the tertiary loop is flexed lengthwise of the path of the stitching, as shown at 45, and the loop spread as shown at 46, (see Figs. 11 and 12), for being received about the button and about the button-shank. Pulling is thereupon exerted upon the supply stretch 47 of the tertiary loop, preferably by pulling upon the supply stretch of the thread for drawing the tertiary loop tightly about the shank-eye of the button, which thereby forms a locking of the stitching (see Figs. 13, 14, 15 and 16), and also preferably forms a knot 48 between the supply end of the supply stretch of the tertiary loop and the secondary loop, this stretching aiding further in tightening the previous knots formed in said stitching. The stretches of the tertiary loop preferably pass crossingly over the stretches of the first-named loop adjacent to the initial hole 14 for forming hitches 49, 50.

The pulling taut of the tertiary loop also has a tendency to force the shank of the button toward the hole from which the tertiary loop protrudes for wedging the rounding 18 of the shank under that end of the primary loop protruding from said hole and forcing said rounding toward the material. The supply stretch of the thread is then passed to the position for the formation of the next stitching for securing the next button in place.

The bight 51 of the tertiary loop is received above both the initial stretch 24 and the supply stretch 25 of the primary loop, (see Figs. 13, 14, 15 and 16), the stretches of

the tertiary loop being located preferably at the side of said stretches of the primary loop located above the outer surface of the material and at the edges and slightly under the rounding of the shank-eye of the button.

The eye-shank of the button is caused to lie close to the outer face of the material to which it is attached, with the shank arranged at right angles to the path of the stitching and in line with the button-hole 19, shown in the coacting flap 20 of the material, which in a shoe represents the button-fly, the button in a shoe being attached to the mating edge of the opposite quarter.

Having thus fully described my invention, what I claim as new and desire to secure by Letters Patent, is:

1. The method of attaching a shank-eye button to material which consists in passing a loop of thread comprising an initial stretch and a supply stretch through the material through the shank-eye of the button and reversely through the material passing the supply-limb of the thread through said loop for forming a supplemental loop, forming a locking loop concatenated with said supplemental loop, and passing said locking loop through the material and about the shank-eye of the button.

2. The method of attaching a shank-eye button to material which consists in passing a primary loop of thread through the material, through the shank-eye of the button and reversely through the material, passing the supply-limb of the thread through said primary loop for forming a secondary loop, drawing said primary loop taut for forming a knot between said loops, passing the supply-limb of said thread through said secondary loop for forming a tertiary loop, and passing said tertiary loop through the material and about the shank-eye of the button and drawing said tertiary loop taut.

3. The method of attaching a shank-eye button to material which consists in passing a primary loop of thread through the material, through the shank-eye of the button and reversely through the material, passing the supply-limb of said thread through said primary loop and drawing said primary loop taut for forming a knot between said loops, passing the supply-limb of said thread through said secondary loop as a tertiary loop, drawing said secondary loop taut for forming a compound knot between said primary and tertiary loops, passing said tertiary loop through the material and about the shank-eye of the button, and drawing said tertiary loop taut for forming a knot between said secondary and tertiary loops.

4. The method of attaching a shank-eye button to material which consists in pass-

ing a loop of thread comprising an initial stretch and a supply stretch through the material at the beginning portion of the stitching and through the shank-eye of the button, and reversely at the end portion of the stitching, passing the supply stretch of said thread from the beginning portion of the stitching through the bight portion of said loop and drawing said loop taut, forming a compound knot at said bight portion with a supplemental loop extending therefrom, passing said supplemental loop through the material to the face side thereof at the beginning portion of the stitching and about the shank-eye of the button, and drawing said supplemental loop taut.

5. The method of stitching a shank-eye button to material which consists in passing a loop of thread comprising a pair of stretches through the material and through the shank-eye of the button and reversely through the material, passing one of the stretches of said thread through the bight portion of said loop and drawing said loop taut, forming a compound knot at said bight portion with a supplemental loop comprising a pair of stretches extending therefrom, passing said supplemental loop through the material to the face side thereof and about the shank-eye of the button, and drawing said supplemental loop taut with its stretches arranged crossingly over the stretches of said first-named loop.

Copies of this patent may be obtained for five cents each, by addressing the "Commissioner of Patents, Washington, D. C."

6. The method of attaching a shank-eye button to material which consists in passing a primary loop of thread through the material and through the shank-eye of the button, forming a supplemental loop concatenated with said primary loop by a plurality of knots between said first-named loop and the initial stretch of said supplemental loop, with said supplemental loop extending reversely through the material and about the shank-eye of the button and knotting the supply stretch of said supplemental loop to said concatenations.

7. The method of attaching a part to material which consists in passing a loop of thread comprising an initial stretch and a supply stretch through the material in reverse directions and through said part between said passings through the material in reverse directions, passing the supply limb of the thread through said loop for forming a supplemental loop, forming a locking loop concatenated with said supplemental loop, and passing said locking loop through the material about said part.

In testimony whereof, I have hereunto signed my name in the presence of two subscribing witnesses.

WILLIAM F. LAUTENSCHLAGER.
